UNITED STATES PATENT OFFICE.

CHARLES WOOD, OF MOULTON, IOWA.

SWITCH-STAND LOCK.

1,089,177.

Specification of Letters Patent.

Patented Mar. 3, 1914.

Application filed May 11, 1912, Serial No. 696,622. Renewed January 20, 1914. Serial No. 813,275.

To all whom it may concern:

Be it known that I, CHARLES Wood, a citizen of the United States, and a resident of Moulton, in the county of Appanoose and State of Iowa, have invented a new and useful Improvement in Switch-Stand Locks, of which the following is a specification.

My invention is an improvement in switch stand locks, and has for its object the provision of simple inexpensive means in connection with a switch stand for locking the operating lever to the stand, with the switch in open or closed position, wherein the locking means is actuated by the dropping of the operating lever into inactive position.

A further object is to provide means in connection with the locking means for permitting the locking means to be disconnected from the operating lever, in case it should be necessary to operate the switch with no key at hand, to prevent breaking of the lock.

In the drawings:—Figure 1 is a plan view 25 of the improvement; Fig. 2 is a section on the line 2—2 of Fig. 1; and Figs. 3 and 4 are sections on the lines 3—3 and 4—4 respectively of Fig. 2.

In the present embodiment of the invention, the top plate or table 1 of the switch stand has a central opening for the operating shaft or rod 6 of the switch, and is also provided with spaced notches or recesses 2 and 3 in its side edge for receiving the lever or handle 4, which oscillates the rod or shaft. The lever 4 is pivoted to an arm 5, secured rigidly to the shaft 6 above the plate 1. One end of the lever 4 is received in a notch or recess 7 in the outer end of the arm, and a bolt or rivet 8 is passed through the arm and the lever to pivotally connect the lever to the arm. When the lever is not in use, it rests in one of the notches, the particular notch depending upon whether the switch 45 is set for the main line or for the siding. To throw the switch the free end of the lever is swung upwardly until the lever is in alinement with the arm. In such position, the upper end of the lever fits the notch 7, and by swinging the arm to the right or left, the switch is thrown. When the lever is released, it drops into the position of Fig. 2, and by its engagement with a notch 2 or 3 acts to hold the switch closed.

55 The standard switch lock is a spring lock, consisting of a body 11, and a shackle 12.

An angle plate 9—10 is secured to the arm at one side of the notch, the portion 9 being held to the arm by rivets or bolts 9^a. The portion 10 of the angle plate has one of its faces in alinement with the adjacent side wall of the notch 7, and the body 11 of the lock is secured to the said portion, and is held in a position to receive the locking tongue of the shackle, which is carried by the lever. The body is held to an extension 13 on the portion 10 of the plate 9—10, by means of bolts or rivets 14, which pass through the body and the extension. The bolts 14 are of course arranged in such a manner that they do not interfere with the operation of the lock. The extension 13 is provided at its upper edge with a lateral flange 15, which extends across the upper edge of the body. The shackle 12 of the lock is provided at the end remote from the catch 23, with a pair of spaced perforated ears 24, and a slotted lug 25 on the body is received between the ears. A pin or bolt 26 is passed through the ears and the slot of the lug and also through the portion 10 of plate 9—10, the said bolt or pin pivotally connecting the shackle to the body. The shackle is received in a recess 27 in a channel bar 28, having a pair of depending lugs 29 and 30 at each end. The shackle is also provided with a pair of spaced ears 31 at the end adjacent to the catch 23, and the said ears are pivoted to the ears 30 of the channel bar by means of a pin 32. The ears 29 of the channel bar are pivoted to the upper end of lever 4, one ear of the pair being received on one side edge of the lever and the other in a slot 4^a in the lever. A bolt 17 is passed through the ears and the lever for pivotally connecting the channel bar to the lever. The channel bar is longer than the shackle, so that the lever 4 is at the end of the shackle, and the said shackle may rest within the recess of the channel bar.

The pin 32 may be of any desired construction and is held in place by heading one end—the other end by a cotter pin. The outer end of the channel of the channel bar is preferably closed, as shown at 18 and the recess 27 is partially closed by a web 18^a—preferably iron construction. The shackle is held by the channel bar in such a position that when the lever 4 is dropped into either of the recesses 2 or 3 the catch of the shackle is forced into the body, push-

ing the spring latch or bolt aside and locking the shackle to the body. Whenever the lever is so dropped into either recess 2 or 3, the switch is locked, and the action is entirely automatic, no attention whatever being required. It is probable that an emergency might arise when it would be necessary to operate the switch, and when the person desiring to operate the switch would have no key. In such case, where no means is provided, the lock would necessarily be broken. The peculiar connection between the channel bar and the lever 4 however, permits the channel bar to be released from the lever by removing pin 17. To remove the said pin it is not necessary to injure the lock which is left in locked position. It will be evident that when the lever 4 is disconnected from the channel bar the lever may be operated in the usual manner. It will be noted that the slot of the lug 25 permits the shackle to be entirely disconnected from the body.

The closed end 18, and the web 18^a of the channel bar protect the outer end of the shackle, and the inner end is rounded or beveled, as shown at 12^a, Fig. 2, in such manner that the adjacent end of lever 4 acts against the said end to press the catch 23 of the shackle into the lock body.

A shield 13^a is secured to the portion 13 of the angle plate and the said shield extends over the inner end of pin 17 to protect the same. When the shield is knocked off or bent down, the pin 17 may be removed by driving it out.

I claim:—

1. In combination with the switch stand, the operating shaft, and the laterally disposed arm secured to the shaft and provided with a recess for receiving the operating lever when said lever is in alignment with the arm, and the operating lever pivoted to the arm, of means for locking the operating lever to the arm when said lever is swung out of alignment with the arm, said means comprising a padlock composed of a locking body, and a shackle, means for securing the shackle to the lever, said means comprising a channel bar pivoted at one end to the upper end of the operating lever, the shackle being received in the channel of the bar, and a pivotal connection between the opposite end of the channel bar and the adjacent end of the shackle.

2. In combination with the switch stand, the shaft and the operating lever pivoted to the shaft for swinging movement on an axis transverse to the shaft, and secured to the shaft to prevent angular movement of the lever with respect to the shaft, of a padlock comprising a body and a shackle,

means for securing the shackle to the lever, means for connecting the body to the shaft in position to receive the shackle when the lever is dropped into inoperative position, said connecting means for the shackle comprising a channel bar, the shackle being received in the channel bar, a pivotal connection between one end of the channel bar and the lever, and a pivotal connection between the other end of the channel bar and the shackle.

3. In combination with the operating shaft of the switch, the lateral arm secured thereto, the lever pivoted to the arm, and the stand having notches for receiving the lever when in inoperative position out of alignment with the arm, of a padlock shackle carried by the lever and a padlock body carried by the arm for locking the lever out of alignment with the arm and in either notch of the stand, the connecting means for the shackle comprising a channel bar pivoted at one end to the lever and at the other end to the shackle, said shackle resting in the channel, and the connection between the lever and the channel bar being releasable.

4. In combination with the operating shaft of the switch, the lateral arm secured thereto, the lever pivoted to the arm, and the stand having notches for receiving the lever when in inoperative position out of alignment with the arm, of means carried by the lever and the arm for locking the lever out of alignment with the arm and in either notch of the stand, said means comprising a padlock having a body and a shackle, a channel bar for connecting the shackle to the lever, and means for connecting the body to the arm in position to engage the shackle when the lever is moved into engagement with a notch of the stand, the connection between the channel bar and the lever being releasable for the purpose specified.

5. The combination with the switch stand having notches, the operating shaft of the switch, the lateral arm secured thereto, the lever pivoted to the arm and adapted to engage the notches when in inoperative position out of alignment with the arm, of a channel bar connected at one end to the lever, a padlock shackle in the channel of the bar and pivoted thereto at the opposite end from the lever, and a padlock body carried by the stand and in position to receive the catch of the shackle when the lever is in inoperative position.
